UNITED STATES PATENT OFFICE

92,523

DESIGN FOR A COMBINED BICYCLE AND LUGGAGE CARRIER ATTACHMENT OR THE LIKE

George W. Clark, Westfield, Mass., assignor, by
mesne assignments to The Westfield Manufacturing Company, a corporation of Massachusetts

Application September 19, 1933, Serial No. 49,293

Term of patent 14 years

To all whom it may concern:

Be it known that I, GEORGE W. CLARK, a citizen of the United States, residing at Westfield, in the county of Hampden and State of Massachusetts, have invented a new, original, and ornamental Design for a Combined Bicycle and Luggage Carrier Attachment or the like, of which the following is a specification, reference being had to the accompanying drawing, forming a part thereof.

Fig. 1 is a side view of a combined bicycle and luggage carrier attachment showing my new design; and

Fig. 2 is a top view of the same with the seat and parts of the handle bars and the left pedal removed for convenience in illustration.

The design of the chain shown partly in full lines is to be carried throughout the entire chain.

The characteristic feature of the design is in the luggage carrier mounted at the rear of the frame, the lines and proportion of which luggage carrier are coordinated with the lines and proportion of the frame to give a pleasing unity to the combination.

I claim:

The ornamental design for a combined bicycle and luggage carrier attachment or the like substantially as shown and described.

GEORGE W. CLARK.
